Primary Examiner — Janice Hallmark*Assistant Examiner* — Omeed Agilee(57) **CLAIM**

The ornamental design for a tripod, as shown and described.

DESCRIPTION

FIG. 1 is a front elevational view of tripod showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The evenly spaced broken lines and the areas within them depict portions of the tripod that form no part of the claimed design.
